UNITED STATES PATENT OFFICE.

DODSON HASLUP, OF GRAFTON, WEST VIRGINIA.

BOTTLE-CAP REMOVER.

1,376,692.

Specification of Letters Patent.

Patented May 3, 1921.

Application filed April 17, 1919. Serial No. 290,711.

To all whom it may concern:

Be it known that I, DODSON HASLUP, a citizen of the United States, residing at Grafton, in the county of Taylor and State 5 of West Virginia, have invented a new and useful Bottle-Cap Remover, of which the following is a specification.

The present invention relates to milk bottle cap removers, the object being to 10 provide a device which may be readily engaged with the bottle closure and which will facilitate the removal of the closure from the bottle.

A further object of the invention is to 15 provide a milk bottle cap remover which may be readily engaged with the cap to remove the same and at the same time not spilling or splashing the contents of the bottle as is ordinarily experienced in removing these 20 caps by hand.

Still another object of the invention is to provide a device for removing milk bottle caps or closures which may be engaged with the bottle cap and left assembled therewith 25 so that the same may be handled to place the cap back in the bottle, and which will prevent the inner face of the cap from contacting with soiled surfaces when it is removed from the bottle.

30 Another object of the invention is to provide a bottle cap remover which is formed from a blank of sheet metal.

Another object of the invention is to provide an improved device of this general 35 character which is simple in construction, consists of few parts, and which may be manufactured and marketed at a minimum cost.

With the above and other objects and advantages in mind, the invention consists of 40 combinations of elements, arrangements of parts, combinations and operations, which will be hereinafter fully enlarged upon and the inventive features defined in the appended claims, one embodiment of the invention being illustrated in the drawing, wherein:—

Figure 1 is a sectional view of my improved bottle cap removing device assembled 50 with the bottle cap taken on line 1—1 of Fig. 2, a portion of the bottle being shown in cross section;

Fig. 2 is a plan view of the device assembled with a bottle cap; and

55 Fig. 3 is a view like Fig. 1 showing the cap removing device in elevation.

In the drawings, wherein like characters of reference designate like parts in all the views, the numeral 5 denotes a length of metal from which my improved cap removing device is formed and has a large rounded part 6 which constitutes the handle of the device, and also includes the narrow portion 7 which extends at right-angles to the handle 6. This narrow portion 6 is bent at 65 right-angles adjacent its outer end and is extended in parallelism with the handle. The intermediate part of the length of metal is struck out to afford a bottle cap engaging barb which extends in parallelism with 70 the intermediate portion and underlies the same and is offset therefrom, one end of the barb being bent at a slight angle so that the same may be inserted into the cap or bottle closure. 75

When the device is being used the right-angle or upstanding part of the narrow portion of the handle is engaged by the fore-finger of the operator while the rounded part 6 constitutes a thumb engaging member. 80

Formed on the enlarged part 6 is a barb 9 which also may be used in removing the bottle cap. An opening 10 is formed in this enlarged part and is adapted to engage upon a nail or the like when the device is not in 85 use. After the closure is extracted from the bottle, the device may be left engaged in the same, and upon placing the closure upon a table or the like, the device supports it in a position where the inner face of the same 90 will not contact with the surface of the table.

This embodiment of the invention is merely illustrative and it is to be understood that the same is subject to minor changes 95 and improvements, and that my limits of such changes are only governed by what is claimed.

What is claimed is:—

1. A bottle cap remover formed from a 100 length of metal bent at right angles adjacent its ends and extended in parallel relation, the parallel parts constituting a fore-finger engaging member and a thumb engaging member respectively, and a single bottle cap 105 engaging barb struck from the intermediate part of the metal and extending beneath the same and projecting to the fore-finger engaging member and no farther, the barb being of substantially the same length as the 110 intermediate part, and extending parallel with said part.

2. In a bottle closure removing device, a length of sheet metal including an enlarged apertured portion and a reduced portion extending laterally therefrom, the enlarged portion constituting a thumb-engaging member, the reduced portion being extended at right-angles to the thumb-engaging member, the outer end of the reduced portion being flat and bent at right-angles and extended substantially in parallelism with the thumb-engaging member to afford a forefinger engaging member, and a bottle closure engaging barb struck from the intermediate part of the metal and totally underlying and extending parallel to said intermediate part and within the confines of said right angularly extended members.
3. In a bottle cap remover, a length of metal having its opposite ends bent substantially at right angles, one end consisting of a thumb-engaging member and the other consisting of a forefinger-engaging member, and a cap engaging barb struck from the intermediate portion of the length and extending entirely parallel to said intermediate portion

and with its free end terminating at the inner face of the forefinger-engaging member.

4. In a bottle cap removing device a length of sheet material bent at right angles adjacent its ends, the bent up portions extended in parallelism, one of said right angularly extended members consisting of a thumb engaged member, the other right angularly extended member consisting of a forefinger engaging member and both of said members being rectilinearly extended throughout the surfacial area thereof, and a bottle cap engaging barb struck from the intermediate part of the length of material at right angles to said members and underlying the intermediate member parallel thereto, the barb being of a length as not to project beyond the same.

In testimony that I claim the foregoing as my own, I have hereto affixed my signature in the presence of two witnesses.

DODSON HASLUP.
